Specification for Design.

Patented Feb. 11, 1913.

Application filed October 12, 1911. Serial No. 654,367. Term of patent 14 years.

To all whom it may concern:

Be it known that I, ROBERT M. DE VIGNIER, citizen of the United States, residing at Hollis Terrace, in the county of Queens and State of New York, have invented a new, original, and ornamental Design for Drop-Shutters, of which the following is a specification, reference being had to the accompanying drawing, forming part thereof.

In the drawing Figure 1 is a perspective view of a drop shutter showing my new design, and Fig. 2 is an elevation showing said drop shutter in front view.

I claim:—

The ornamental design for a drop shutter, as shown.

In witness whereof, I, hereunto subscribe my name this 10th day of October A. D., 1911.

ROBERT M. DE VIGNIER.
